UNITED STATES PATENT OFFICE.

STEPHEN RICHMAN ROBERTS, OF CENTRALIA, MISSOURI.

WASHING-MACHINE.

1,105,699.

Specification of Letters Patent.

Patented Aug. 4, 1914.

Application filed May 3, 1913. Serial No. 765,343.

To all whom it may concern:

Be it known that I, STEPHEN R. ROBERTS, citizen of the United States, residing at Centralia, in the county of Boone and State 5 of Missouri, have invented certain new and useful Improvements in Washing-Machines, of which the following is a specification, reference being had therein to the accompanying drawing.

10 This invention relates to a washing machine of the pounder type, and the principal object of the invention is to provide a machine in which the clothes pounder is permitted to move horizontally as well as vertically, thereby permitting the clothes pounder to cover a large extent of space.

Another object of the invention is to provide the clothes pounder with a hinge construction which will not only permit of this 20 free action but which will also limit the pivotal movement of the cover when being raised.

Another object of the invention is to provide an improved type of pounder.

25 With these and other objects in view this invention consists of certain novel combinations, constructions, and arrangements of parts as will be hereinafter fully described and claimed.

30 In the accompanying drawings:—Figure 1 is a top plan view of the improved clothes washer. Fig. 2 is a side elevation of the improved washing machine. Fig. 3 is a vertical sectional view through the machine.

35 Fig. 4 is an enlarged perspective view showing the construction of the hinge. Fig. 5 is a perspective view of the pounder. Fig. 6 is a view looking at the inner face of the pounder head.

40 The invention comprises a tub 10 which is preferably of a substantial elliptical shape, and thus of greater length than width, and which is supported by the legs 11 fitting in the sockets 12. A tray 13 extends 45 from one end of the tub to permit a wringer to be connected with the tub and to provide a receptacle in which the clothes may rest before being passed through the wringer. The usual handles 14 for moving the tub 50 from one place to another are provided.

A cover 15 is provided for the tub and carries a depending flange 16 fitting within the tub and holding the cover in the proper position. The outer edge portion 17 of the 55 cover is bent upwardly and slightly curved as shown in Fig. 4 to form a pocket in which

the upper edge of the tub fits. An elongated neck 18 extends from the center of the cover 15 and is braced by the supporting plate 19 shown in Fig. 3.

60 The cover 15 is pivotally connected with the tub by means of the hinge shown in Fig. 4 which hinge comprises the strips 20 and 21 secured to the tub and cover respectively and the pin 22 passing through the coiled 65 end portions 23 of the strips 20 and 21. The upper portions of the strips 20 are bent outwardly as shown at 24 to form pockets in which the edge portion 17 of the cover fits to permit the cover to be swung upwardly when desired to obtain access to the 70 interior of the tub.

75 Strips 25 are pivotally mounted upon the pin 22 between the strips 20 and 21 and have their upper ends coiled about the pins 26 extending from the plate 27. This plate 27 will, therefore, be pivotally mounted, thus permitting the lever 28 to be given a vertical movement. The inner end of the lever is secured to the plate 27 by means of 80 a bolt 29, which bolt pivotally connects the lever with the plate, thus permitting the lever to have side play as indicated by the dotted line position in Fig. 1. The strips which form the lever 28 are twisted as shown 85 at 30 and are then carried in contacting relation for a portion of their length and have their free end portions 31 separated and secured upon opposite sides of the handle 32 by means of the bolts 33.

90 The clothes pounder comprises a head formed from a plurality of pans 34, three pans being shown in the accompanying drawings. It is, of course, understood that as many pans may be provided as desired, 95 the number being regulated according to the size of the washing machine. These pans are held together by rivets 35 and are provided with central openings through which the threaded inner end portion of the shaft 100 36 passes. This shaft 36 passes through a reinforcing strip 37 carried by the outer pan and is held in place by the inner and outer nuts 38. This shaft 36 passes through the neck 18 and is pivotally connected with the 105 lever by means of the pin 39 passing through openings 40 and 41 in the shaft and lever.

110 When operating this washing machine the clothes are placed in the tub and then the water poured in until a sufficient amount of water is in the tub. The cover is held in the raised position when the tub is being filled

by the strips 25 resting against the side of the tub, thus causing the lever to form a supporting arm for holding the cover in a substantial horizontal position to one side of the 5 tub. As soon as the tub is filled the cover is turned down upon the tub and the clasp 42 snapped in place to prevent the cover from being accidentally raised when operating the 10 pounder. This clasp 42 comprises a hasp 42' hingedly secured to the top or cover 15 15 and a member 42² having a spring head 42³ is attached to the tub 10. The hasp 42' is provided with an opening 42⁴ into which the spring head 42³ is adapted to be positioned 20 when the device is in a locked position. The handle 32 is now grasped and the lever moved vertically to cause the head to create a circulation of water in the tub. By having the lever pivotally mounted as described 25 and shown in Fig. 4 the pounder may be given vertical movement and the lever may be also moved longitudinally in the neck 18 from the center to the ends of the neck as indicated by the dotted line position in Fig. 1, thus permitting the pounder to be moved 30 toward the ends of the tub and thus the clothes in the end portion of the tub operated upon.

Having thus described the invention what 30 is claimed as new, is:—

1. A clothes washing machine comprising a tub, a cover for said tub, strips secured to said tub and cover and having their free end

portions coiled to form hinge ears positioned in alinement, a pivot pin passing through 35 said hinge ears, strips pivotally mounted upon said pivot pin, a plate pivotally mounted between the free end portions of said last mentioned strips, a lever pivotally connected with said plate and extending across said 40 cover, and a clothes pounder positioned in said tub and having its shaft passing through an elongated opening in said cover, the pivotal mounting of said lever permitting said pounder to have vertical movement 45 through said tub and longitudinal movement in the opening formed in said cover.

2. A washing machine comprising a tub, a cover fitting upon said tub, an elongated neck extending from said cover, a clothes pounder positioned within said tub and having its shaft extending through said neck, a support pivotally connected with said tub, and a lever pivotally connected with said support for universal movement whereby 50 said pounder may be given vertical movement through said tub and longitudinal movement through said neck, said neck guiding the movement of said pounder.

In testimony whereof I hereunto affix my 60 signature in presence of two witnesses.

STEPHEN RICHMAN ROBERTS.
